[57] ABSTRACT

A game apparatus comprising a board with an array of upstanding pegs which have flat top surfaces. Sets of counters similar to checkers but with highly polished surfaces are provided, the counters designed to be deposited on selected pegs by means of a manual implement. The latter is a pair of sticks similar to Chinese chopsticks and having rounded, highly polished ends. Each counter is designed to be grasped between one of the ends of the sticks and carried for deposit as stated, this process imposing a hazard.

BOARD GAME APPARATUS

My invention relates to board games, and more particularly to the type in which assorted pieces or counters are applied to parts arranged on the game board.

One object of the invention is to afford manual handling of the counters for introductory placement, but require their handling and manipulation by a hazardous implement for procuring movements and placements during the playing of the game.

Another object is to employ a set of implements in the nature of chopsticks and held in one hand by each player, such implements being usable to pick up, move and deposit the counters in relation to an array of pegs mounted in the center field of the game board, the counters being in sets of a different color for each player and round and polished in order to require skillful handling with the chopstick implements in order not to drop from the same.

A still further object is to provide a game which is simple and presents hazards which challenge the skill and dexterity of the players.

A better understanding of the invention may be gained by reference to the accompanying drawing, in which

FIG. 1 is a top plan view of the game board;

FIG. 2 is an enlarged frontal elevation in part, as seen from the line 2—2 of FIG. 1;

FIG. 3 is a perspective view of one of the counters used in playing the game; and

FIG. 4 is a perspective view of a pair of the chopstick implements, as held in the hand for playing the game.

Referring specifically to the drawing, 10 denotes the board of the game, the same being approximately 2 feet square. The parts located on the board are arranged symmetrically to serve two players seated on opposite sides, or three or four players seated on adjacent sides.

Four sets of pegs 11 — nine in each set — are mounted along the sides of the board, the pegs being upstanding dowels with polished surfaces and dark on top. The height of the pegs is approximately three-fourths of an inch, and their diameter the same.

The board also receives an array of dowel-like upstanding pegs 12 in a medial field. These pegs are of the same diameter as the pegs 11, but taller — approximately 1 1/4 inches in height. These pegs have white tops and polished surfaces. There are six pegs on each side forming a square of 36 pegs.

FIG. 4 shows a pair of the chopstick implements 13 and the manner in which they must be held in the hand for playing the game. These implements are not designed with flat surfaces in the manner of Chinese chopsticks for engaging objects broadly and frictionally. On the contrary, the present implements are

round sticks with hemispherical ends as shown, all very smooth and highly polished.

The counter 14 shown in FIG. 3 is similar to checker counters but not as wide, being of a diameter equal to that of the pegs 11 or 12. The counters come in four sets of different colors, each set containing nine counters. Like the board pegs, the counters are smooth and highly polished on all sides.

The game is initiated by depositing each set of counters — one set for each player — on the set of pegs 11 situated in front of the player. This may be done by hand if time is to be saved; or, the counters may be picked up, one by one, by means of the player's chopstick implement and deposited on the row of pegs 11.

The playing of the game, after each set of counters has been deposited as mentioned, involves the placement of counters on selected pegs 12. Since these are taller than the pegs 11, the latter will not present obstacles to reaching the pegs 12 from the side. Since the counters and the tips of the implements are round and very slippery, skillful handling and dexterity will be required to accomplish each placement, with the risk of dropping the counter instead. Various rules may be devised to play the game and define the hazards involved in picking-up, moving or depositing the counters. Thus, a player may lose one point when he drops a counter, or must sacrifice the choice of the selected counter to the next player in such event. A player may score if he accomplishes a line-up of his counters in a vertical, horizontal or diagonal corner-to-corner row of the pegs 12.

It will now be apparent that the present game is not only of a fascinating character, but dependent on skill, dexterity and patience if failures or other penalizing incidents are to be avoided. At the same time, the game is simple enough to be played by both young and old, may be played either by two, three or four people, and should provide an interesting and amusing pastime.

I claim:

1. A game apparatus comprising a board, an array of upstanding pegs thereon, the pegs cylindrical with tops flat and extending to the sides of the pegs, polished circular counters with tops and bottoms flat, and a set of chopstick-like implements usable to pick up and deposit counters on desired pegs, the ends of the implements rounded and polished to render said pick up and deposit hazardous.

2. The apparatus of claim 1, said board being square with outer sets of the pegs located on each side for the introductory deposit of counters, and an inner group of pegs approachable over the outer set for selective deposit of counters on pegs of the inner group.
